United States Patent

Des. 241,220
Patented Aug. 31, 1976

241,220

PORTRABLE MICROWAVE OVEN

Thomas J. Binzer, Louisville, Ky., assignor to General Electric Company

Filed June 2, 1975, Ser. No. 582,644

Term of patent 14 years

Int. Cl. D7—02

U.S. Cl. D7—128

FIG. 1

FIG. 2

FIG. 3

FIG. 1 is a perspective view of a portable microwave oven, showing my new design;

FIG. 2 is a side elevational view thereof;

FIG. 3 is a top plan view thereof.

The side of the oven which is not shown is a mirror image of the side disclosed in FIG. 2.

I claim:

The ornamental design for a portable microwave oven, as shown and described.
